INVENTOR
S. H. CAMPBELL
BY *S. H. Campbell*
ATTORNEY

UNITED STATES PATENT OFFICE.

STERLING H. CAMPBELL, OF ST. LOUIS, MISSOURI.

UNCOUPLING DEVICE.

1,358,362.

Specification of Letters Patent. Patented Nov. 9, 1920.

Application filed December 13, 1919. Serial No. 344,553.

To all whom it may concern:

Be it known that I, STERLING H. CAMPBELL, a citizen of the United States of America, residing at the city of St. Louis, State 5 of Missouri, United States of America, have invented a certain new and useful Uncoupling Device, of which the following is such a full, clear, and exact description as will enable any one skilled in the art to 10 which it appertains to make and use the same, reference being had to the accompanying drawings, forming part of this specification.

My invention relates to an uncoupling device such as is used to operate the locking pin of a coupler of the vertical plane type to release the knuckle.

In the accompanying drawings which illustrate an uncoupling device made in accordance with my invention together with a portion of a railway car to which the same is applied, Figure 1 is a front elevation, Fig. 2 is a top plan view, Fig. 3 is an enlarged plan view of some of the parts 20 shown in Fig. 2, Fig. 4 is an enlarged front elevation of the bracket, Fig. 5 is a side view of the bracket and Figs. 6 and 7 are a plan view and a front elevation, respectively, showing a modification.

10 indicates a railway car provided with a draw bar 11 and carrying a coupler head 12 provided with the usual pin 13 for locking the knuckle 14. 15 is an operating lever provided at its outer end with a handle 16 25 and supported in a bracket 17. The lever 15 is provided with an extension 18 passing through the eye of the coupler pin 13 and provided with a return bend 19 preferably formed in a horizontal plane so as not to 30 project above the top of the pin 13. The extension 18 is provided with a pair of apertures 20 and 21 respectively, as best shown in Fig. 3. The extension is secured to the main lever 15 by means of a bolt or rivet 22 35 passing through the said lever and through the opening 20 in the extension. The end of the extension 18 is preferably curved at 40 23. The main part 15 of the lever is provided with a projection 24 extending at 45 right angles to the body of the lever and passing through the opening 21 which is somewhat elongated in form to allow the necessary lateral movement between the body of the lever and the extension. The 50 55 extension 24 is provided with an upturned

end 25 for limiting the lateral movement of the extension.

In Figs. 6 and 7, I have shown a modification in which the extension 18 is provided with a single slot 26 adapted to receive a flat projection 24^A. The shape of this projection serves to hold the extension against rotary motion. A rivet 27 limits the lateral movement of the extension in 60 this modification.

The bracket 17 is secured to the side of the car 10 by any suitable means such for instance as bolts or rivets 28 and is provided with a vertical slot 29 adapted to receive the lever 15 and to allow its movement in 70 vertical plane. The lever 15 is provided with a recess 30 adapted to bear on the curved bottom 31 of the slot 29. In order to hold the lever in operative relation to the curved bottom 31, I provide the bracket 75 with a pair of lugs 32 as best shown in Fig. 3. The lugs are cast in the form shown in dotted lines in this figure and are adapted to be bent around a locking pin 34. The pin 34 is adapted to be swung across the 80 open top of the slot 29 to lock the lever in position. The pin 34 is provided with a head 37 and is locked in position by spreading the two parts of the slotted end. In this way, the parts are securely locked together but the lever may be released by bending the parts of the slotted end together and swinging the bolt 34 on its pivots. At 85 the same time there are no parts which may become lost so as to disable the device. 90

The operation of my device will be evident. The locking pin 13 is raised by depressing the handle 16 so as to swing the lever 15 in a vertical plane and at the same time the necessary movement between the 95 coupler head and car is provided by the sliding of the extension 18 in the eye of the locking pin and by the lateral movement between the extension 18 and the body 15 of the lever.

Having fully described my invention, what I claim as new and desire to secure by Letters Patent of the United States is:

1. In an uncoupling device, the combination with an operating lever having a main part provided with an angular projection, of a bracket carrying said lever, an extension permanently secured to said main part and provided with an aperture through which said angular projection passes, 105 110

whereby the lever must be removed from the bracket to disengage the extension from the coupler eye.

2. In an uncoupling device, the combination with an operating lever having a main part provided with an angular projection, of an extension having a curved end lying against the front face of said main part and provided with an aperture, fastening means passing through said aperture and securing said extension to said member in rocking relation thereto, and a second aperture intermediate of the length of said extension

through which said angular projection passes.

3. In an uncoupling device, the combination with an operating lever pivoted to move in a vertical plane and having an angular projection, and a flat extension secured to the front face of said lever in rocking relation thereto and provided with an aperture through which said angular projection passes.

In testimony whereof I have hereunto set my hand and affixed my seal.

STERLING H. CAMPBELL. [L. S.]
